UNITED STATES PATENT OFFICE.

ADOLF BÜHLER, OF SONNENHUGEL, UZWIL, SWITZERLAND, ASSIGNOR TO THE FIRM
GEBRÜDER BÜHLER, OF UZWIL, SWITZERLAND.

CYLINDER MILL.

Application filed July 25, 1922. Serial No. 577,414.

To all whom it may concern:

Be it known that I, ADOLF BÜHLER, citizen of the Republic of Switzerland, residing at Sonnenhugel, Uzwil, Switzerland, have 5 invented certain new and useful Improvements in Cylinder Mills, of which the following is a specification, reference being had therein to the accompanying drawing.

The present invention relates to improvements in cylinder mills and particularly to a device for effecting an automatic lubrication with cylinder mills utilized in the chocolate industry and the like.

With cylinder mills such as for instance 15 are utilized for grinding the raw products utilized in the chocolate industry, it is of course of great importance to take precautions with regard to obtaining utmost cleanliness in the working.

20 This end is attained by the cylinder mill of the present invention, according to which the two lateral shields of the mill form at the same time the walls of lateral compartments or boxes serving also as a reser- 25 voir containing the lubricant which boxes enclose the part of the automatic lubricating device appertaining to the respective side as well as the whole of the driving gear, the bearings and the mechanism for adjusting the center distance of the rolls.

30 In this way the lubricating device, the lubricant and the parts to be lubricated are arranged within the two lateral compartments whereby an enhanced cleanliness of the working is ensured.

A constructional example of a cylinder mill according to the present invention is 35 illustrated on the accompanying drawing. The figures of the drawings show some parts in a diagrammatic manner, generally those parts necessary for the explanation of the invention alone being illustrated. In the drawing:

40 Figs. 1 and 2 show the two lateral ends of the cylinder mill some parts being shown in section and the cover for the lateral compartments being removed;

45 Fig. 3 is a front view of the cylinder mill with parts shown in section.

50 The cylinder mill illustrated and adapted to treat the raw product for making chocolate comprises five rolls 1, 2, 3, 4, 5 cooperating in pairs. The product to be ground is supplied by means of a hopper 6

to the uppermost pair of rolls 1, 2 from 55 where it passes in between the pair of rolls 2, 3, and 3, 4 and 4, 5. 7 denotes the pulley by means of which the roll 5 is rotated. Through the interposition of the gear wheels 8, 9 the roll 4 is actuated, the gear 60 wheels 10, 11 rotate the roll 3, the gear wheels 12, 13 rotate the roll 2 and the gear wheels 11, 14 impart rotation to the roll 1. The rolls 2, 4, 5 may be adjusted in their distance relatively to the adjacent rolls in 65 order to alter the quantity passing between the rolls, to this end the axle pins of the rolls are each mounted in a swingably arranged member 15. The members 15 may be swung around their fulcrum pins 27 by 70 means of screw spindles 28 and hand wheels 16, an actuation of the hand wheels 16 causes the center distance between cooperating 75 rolls to be varied.

The two side shields of the cylinder mill frame form at the same time part of the walls of the two lateral compartments or boxes 17, 18, the interior of which is made accessible by unscrewing the detachable covers 17¹ or 18¹ respectively. The lower 80 parts of the compartments 17, 18 forming reservoirs for the lubricant for instance oil, are connected to each other by a pipe 19 so that these reservoirs communicate with each other. Inside the compartment 17 the 85 oil for lubrication purposes is drawn by a pump 20 driven from the pulley 7 by means of gear wheels 29, 30; the oil delivered by the pump is supplied to the single bearings of the axles of the rolls on one side of the 90 cylinder-mill by means of the pipes 21, 25 and 26. The superfluous oil and the waste oil drops into the reservoir portion of the respective compartment where it mixes with the oil stored in the reservoir. To the 95 bearings of the axles of the rolls on the other side of the cylinder mill the oil is supplied from the same pump 20 through a pipe 23 leading across the cylinder-mill and from there to similar distributing pipes 100 25 and 26. The distributing pipes are sufficiently flexible to allow an operation of the mechanism for adjusting the center distance of the rolls.

With a cylinder mill constructed as described above the operator is protected from getting into contact with the lubricant and with the parts to be lubricated; a cylinder

mill of this type may also be used for grinding other products than those used in the chocolate industry. The utilization of the side shields as walls for the lateral compartments together with the disclosed arrangements of the automatic lubrication admits of a considerable saving in space in the axial direction of the rolls, i. e., of a compact design of the cylinder mill.

10 I claim:

1. In lubricating mechanism for cylinder mills, the combination with two hollow frame members between which the cylinders are mounted and in which the driving gears at the ends of said cylinders are arranged; of a removable cover for each frame member, oiling devices for the bearings in the respective members, a pipe extending across the mill between the frame members and a
- 15 pump within one of said frame members and directly supplying oil to the oiling device therein and also supplying oil through
- 20

said pipe to the oiling device in the other frame member.

2. In a lubricating mechanism for cylinder mills, the combination with two hollow frame members between which the cylinders are mounted and in which the driving gears at the ends of said cylinders are mounted; of a removable cover for each frame member above the bottom thereof, oiling devices in each member, a pump arranged within one of said members, pipe connections between the pump and the respective oiling devices, and a liquid level equalizer extending from the bottom of one frame member to the other and connecting the oil chambers formed in the bottoms of said members, said pumps being supplied with oil from oil chamber in the member in which the pump is arranged.

In testimony whereof I have affixed my signature.

ADOLF BÜHLER.
